RADIO TRANSMITTING APPARATUS

Application filed March 20, 1928. Serial No. 263,010.

This invention relates to radio transmitting systems and has to do most particularly with systems intended for operation at extremely high radio frequencies.

5 The primary object of the invention is to obtain frequency stability.

It has been the practice heretofore in vacuum tube radio transmitting systems to utilize a so-called master oscillator of relatively small power output and associate this with the transmitting antenna through the medium of a vacuum tube relay or power amplifier which is asymmetrically conductive and therefore capable to a large extent of 10 electrically isolating the master oscillator from the antenna, thereby preventing the frequency of the oscillator being unduly affected by variations of the antenna constants. This practice works out satisfactorily 15 at ordinary frequencies and at fairly high frequencies; but when working with extremely high frequencies, say at wave lengths of the order of 5 to 100 meters and thereabouts, it is found that the intermediate or power 20 amplifiers do not provide adequate isolation 25 from the master oscillator, and consequently do not perform as well in the matter of maintaining frequency stability as they do at the lower radio frequencies.

30 The present invention comprehends the utilization of a master oscillator which is magnetically and electro-statically isolated from both the transmitting antenna and the power amplifier or intermediary relay and 35 is coupled to the input of the latter only through a radio linkage which provides a unidirectional coupling.

More specifically, the present invention 40 contemplates the combination with a transmitting antenna of a thermionic amplifier comprising one or more stages of amplification, the input end of which is coupled to a small receiving antenna which is arranged to pick up radio waves which are propagated 45 from a master oscillator of relatively small

power and located in the near vicinity. By such an arrangement, as will be hereinafter more clearly pointed out, the master oscillator is not influenced by either the transmitting antenna or the power amplifier or intermediary relay and as a consequence will operate continuously substantially without frequency fluctuation.

50 The invention will be described in detail with reference to the accompanying drawing.

Referring to the drawing, I have shown a small master oscillator 11 preferably of the electron relay type. As my apparatus is designed particularly for operation upon relatively short wave-lengths, the frequency 55 of the master oscillator is particularly sensitive to changes in the electrical characteristics of its circuits. When such an oscillator is coupled to the input of an electron relay amplifier, it is difficult to maintain it at a constant frequency, due in part to reaction of the 60 amplifier upon the oscillator. Furthermore in such case various adjustments made upon the amplifier serve to affect the frequency 65 of the oscillator.

70 As outlined above, in accordance with my invention I couple the output of the oscillator 11 to a local antenna 12. This antenna is preferably of relatively small dimensions so that even tho it receives energy continuously 75 from the master oscillator, it will not interfere with the transmission of modulated energy from the main antenna to be presently described. Its small dimensions also prevent it from effecting undesired variations in the 80 frequency of the oscillator.

85 The remainder of the transmitting apparatus comprises an electron relay amplifier 13 the output circuit of which is coupled to the usual main antenna 14. It is apparent that amplifier 13 may have one or more amplifier stages, and in this particular case I have illustrated an intermediate amplifier relay 16, and a power amplifier relay 17. The input to amplifier 16 is coupled to a 90

local antenna 18, similar to the local antenna 12.

Antenna 18 and the input of amplifier 16 are tuned to the frequency of master oscillator 11, or to the frequency of the energy being radiated by local antenna 12. Local antennæ 12 and 18 are located sufficiently close together that antenna 18 intercepts an appreciable amount of energy radiated from antenna 12, but not so close that capacitative or inductive coupling is provided. In other words in so far as inductive or capacitative coupling is concerned, master oscillator 11 is entirely isolated from the electron relay amplifier 13. I have found that the energy picked up by the local antenna 18 is sufficient to excite the electron relay amplifier, so that the output of this amplifier has sufficient power to supply the main antenna 14.

In order to avoid disturbing the adjustments of the master oscillator 11, I prefer to effect modulation of transmitted energy by means associated with the remainder of the transmitting apparatus. For example I have shown a key 19 inserted in the grid circuit of amplifying relay 16, whereby the signal energy may be modulated in accordance with telegraph code combinations.

With apparatus constructed in accordance with this invention, the master oscillator may be operated at short wave-lengths of between 5 to 100 meters, and its frequency will remain sufficiently constant for all practical signaling purposes. Its frequency will not vary during operation of the remainder of the apparatus or when adjustments are being made in the amplifier 13 or the main antenna. I have found that with such apparatus I may dispense with the use of special frequency controlling devices such as quartz crystals and the like.

The invention is not to be confused with systems in which signals are received from a remote point and relayed to another station. My invention is designed to primarily solve the problem of keeping the frequency of a master oscillator relatively constant, and the oscillator in this case is located at the same station as the main transmitting equipment. Furthermore in my apparatus the high frequency energy received by the local antenna 18 is not integrated or detected before being amplified and impressed upon the main antenna 14.

I claim:

A radio station transmitting equipment comprising a main antenna, electron relay amplifying means having output and input circuits, the output circuit being coupled to said main antenna, said means serving to amplify oscillatory energy impressed upon its input circuit without integration, a relatively small local antenna coupled to said input circuit, a local master oscillator of the electron relay type and operative to generate

oscillations of radio frequency, and another local antenna coupled to said oscillator, said last local antenna being sufficiently small as to have substantially no tendency to vary the frequency of the oscillator, said local oscillator and said last local antenna being electrically isolated from said amplifying means and said first local antenna and transferring energy thereto solely by radiation.

In testimony whereof, I have hereunto set my hand.

WILLIAM M. BROWER.
